UNITED STATES PATENT OFFICE.

GEORGE S. BENJAMIN, OF DETROIT, MICHIGAN.

WINDOW MOUNTING.

Application filed July 21, 1924. Serial No. 727,265.

To all whom it may concern:

Be it known that I, GEORGE S. BENJAMIN, a citizen of the United States, residing at Detroit, in the county of Wayne and State 5 of Michigan, have invented a new and useful Window Mounting, of which the following is a specification.

This invention relates to windows and particularly to a hinge mounting for a 10 slideable window sash.

It is an object of the invention to provide a mounting for the sliding sashes of a window which will combine in a unitary member both a hinged and slideable support for 15 the sash permitting the latter to be raised and lowered and to be swung inwardly without interference one with the other.

The invention further consists in certain structural features of formation of the hinge 20 member adapting it to establish a sliding engagement with a guide member.

A preferred embodiment of the invention is illustrated in the accompanying drawings, in which,

25 Figure 1 is a view in interior elevation of a window equipped with the improved mounting, in which the sashes are shown in their normally closed positions.

Figure 2 is a perspective view of one of 30 the hinge members of the lower sash, detached.

Figure 3 is a vertical sectional view taken on line 3—3 of Figure 1.

Figure 4 is a transverse sectional view 35 through the upper sash with the lower sash shown in plan, both sashes being swung inwardly at right angles to their normal positions.

Figure 5 is a sectional detail view taken 40 on line 5—5 of Figure 4, showing primarily a provision for attaching the counterbalance cord to one of the hinge members.

In these views the reference characters 1 and 2 designate respectively the upper and 45 lower sashes of the window, and 3 and 4 indicate the side jambs of the window frame. Mounted upon the jamb 3 are two adjacent channel-shaped guides 5, preferably of sheet-metal, extending, one opposite to each sash 50 the full height of the window opening. Said guides have spaced inward extensions 6 from the edges of their side walls, and are secured to the jamb 3 by screws 7.

Each of the sashes has secured upon one

edge thereof the leaves 8 of a pair of spaced 55 hinges 9, the complementary leaf 10 of each hinge being formed to slidably engage a corresponding channel guide and thus adapt said hinges to establish both a pivot support and a slideable mounting for the sash. 60

The slideable engagement between the channel guide 5 and the complementary leaf 10 of the hinge is established by forming in opposite edges of said leaf opposed recesses or channels 11 for receiving freely the 65 respective flanges 6 of said channel guide to retain the parts against lateral displacement, yet slideably interengaged, as clearly shown in Figure 4.

It will be understood that the pivotal 70 engagement for the sashes is established by the pins 12 of the hinges and in order that both sashes may at the same time be swung to positions transverse to the frame of the window without interfering with each other, 75 both leaves of each hinge are intermediately bent at a right angle, and the hinges of the respective sashes are oppositely positioned, so that the pins 12 of the hinges of the upper sash are offset away from the jamb 3, 80 while those of the lower sash hinges are offset toward said jamb and disposed relatively close thereto. The position of the sashes as shown in Figure 4 is permitted by the described location of the hinge pins. 85

A suitable stop strip 13, secured to the jamb 4, forms an outer guide for the upper sash. The two sashes overlap each other sufficiently in their normally closed positions to prevent inward swinging of said upper 90 sash and the lower sash may be held against inward swinging by any suitable releasable means, such as a removable stop strip or latch (not shown).

Each sash may be counterbalanced by a 95 weight 14 suspended by a cord 15 passing over a pulley 16 journaled in the upper end of the jamb 3. The attachment of said cords to the sashes is effected preferably by forming the upper leaf 10 of each sash 100 with an integral hook or the like 17 to detachably receive eyes or loops on said cords.

It will be observed that by the described construction the hinge as a unit serves to establish a direct connection between the sash 105 cord and sash as well as a pivotal and slideable connection between the sash and channel guide, eliminating all intermediate

parts usually required for mounting windows of this character and thus greatly simplify and reducing the parts and cost of manufacture.

5. What I claim is:

1. In a window construction, the combination with a frame having a window opening, of a channel guide mounted upon said frame within said opening and formed with a pair of opposed flanges, a closure for said opening, and a hinge comprising a leaf secured to said closure, and a complementary leaf having a portion of increased thickness, the opposite edges of which are grooved for sliding engagement with said flanges.

10. 2. In a window construction, the combina-

tion with a frame having a window opening, of a channel guide mounted upon said frame within said opening and formed with a pair of opposed flanges, a closure for said opening, and a hinge comprising a leaf secured to said closure and a complementary leaf bent to form substantially a right angle, and increased in thickness at one side of said angle, and grooved upon opposite edges for 20 sliding engagement with said flanges, and a projection from said grooved portion into said channel guide for engagement by a counter-balance cord.

25. In testimony whereof I sign this specification.

30. GEORGE S. BENJAMIN.
